LUDGER E. LA BRIE INVENTOR
BY

LA BRIE

ATTORNEY

UNITED STATES PATENT OFFICE

LUDGER E. LA BRIE, OF SOUTH BEND, INDIANA, ASSIGNOR TO BENDIX BRAKE COMPANY, OF CHICAGO, ILLINOIS, A CORPORATION OF ILLINOIS

BRAKE SHOE

Application filed February 14, 1927. Serial No. 168,044.

This invention relates to brake shoes, and is illustrated as embodied in shoes for an internal expanding automobile brake.

An important object of the invention is to provide strong and light, but inexpensive, shoes, by building each shoe up of an arcuate outer band, for the lining, and a flat stiffening web member secured to the band by a series of spaced spot-welds. Preferably the web member has a series of projections about its outer edge, which are shown as engaging the inner face of the outer band, so that all of the spot-welds may be made at once, by arranging one electrode in engagement with the outer band and forming the other to grip the web member, so that currents are sent simultaneously in parallel through all of the projections.

Another feature relates to positioning the shoe laterally by a cam device having parts straddling the end of the stiffening web and engaging rollers on opposite sides of the shoe.

The above and other objects and features of the invention will be apparent from the following description of one illustrative embodiment shown in the accompanying drawing, in which:

Figure 1 is a vertical section through a brake, just inside the head of the drum, showing the novel shoes in side elevation;

Figure 2 is a cross-section through one of the end shoes, on the line 2-2 of Figure 1;

Figure 3 is a cross-section through the center or secondary shoe, on the line 3-3 of Figure 1;

Figure 4 is a partial section on the line 4-4 of Figure 1, showing the positioning of the shoes by the cam; and

Figure 5 is a section through the brake anchors on the line 5-5 of Figure 1.

The illustrated brake includes a rotatable drum 10, at the open side of which is a backing plate or other support 12, and within which are arranged a primary shoe 14, an auxiliary shoe 16, and a secondary shoe 18.

Each of the shoes 14 and 16 includes an outer arcuate band 20, to which the lining 22 is riveted or otherwise secured, and a flat stiffening web member 24, which extends be-

yond the lower end of band 20 as a pivot arm. Each web member 24 is notched along its outer edge to form a series of projections 26 engaging the inner face of band 20. In manufacturing the shoe, one electrode engages band 20, and the other electrode is formed to grip the web member 24, so that the current divides in parallel among the projections 26, which are thus simultaneously spot-welded to the band 20.

Shoe 18 differs from the primary and auxiliary shoes principally in that band 30, carrying the lining 32, is stiffened by two parallel webs 34 notched to form series of projections 36 spot-welded to band 30 as described above.

The primary shoe 14 is arranged with the end of its web member 24 extending between web members 34, and connected to them by a floating pivot 38. Secondary shoe 18 is mounted at its opposite end on a fixed pivot or anchor 40, while auxiliary shoe 16 is arranged with its stiffening web member 24 extending between web members 34 and pivoted on an anchor 42.

The brake is applied by novel means shown as including a cam device 44 slotted to form parts embracing the ends of web members 24 of shoes 14 and 16 to position the shoes laterally. The cam device 44 engages pairs of rollers 46 mounted on opposite sides of the shoes. The cam 44 applies shoes 14 and 16 against the resistance of a return spring 48, whereupon shoe 14 applies shoe 18 against the resistance of an auxiliary return spring 50.

While one illustrative embodiment has been described in detail, it is not my intention to limit the scope of the invention to that particular embodiment, or otherwise than by the terms of the appended claims.

I claim:

1. A brake shoe having a generally-arcuate outer band, and a flat radial stiffening web member having along its outer edge a series of spaced radial projections spot-welded to said band.

2. A brake shoe having a substantially-imperforate generally-arcuate outer band, and a flat radial stiffening web member having along its outer edge a series of spaced

radial projections spot-welded to the inner face of said band.

3. A brake shoe having a generally-arcuate outer band, and a radial stiffening web member secured at its edge surface to the inner face of said band by a series of spaced spot-welds.

4. A brake shoe having a curved outer band member and a stiffening member engaging the inner face thereof, one of said members being formed with radial projections engaging the other and being welded to the other.

In testimony whereof, I have hereunto signed my name.

LUDGER E. LA BRIE.
